FLUID POWERED WASHING MACHINE

Artie F. McFarland, Houston, Tex., assignor to
 McFarland Manufacturing Corporation, Houston, Tex., a corporation of Texas

Application January 11, 1946, Serial No. 640,543

5 Claims. (Cl. 68—122)

1

This invention relates to washing machines and refers more particularly to washing machines powered by hydraulic rams and the tripping mechanism for the valve which controls the flow of hydraulic fluid to the ram.

An object of this invention is to provide a hydraulically powered washing machine of the type having a reciprocating agitator in which operation of the agitator is regulated by manual manipulation of a single control member.

Another object is to provide a washing machine of the type having a reciprocating agitator driven by a hydraulic ram in which the agitator may be reciprocated between selected levels within the washer tub.

A further object is to provide a washing machine of the type having a reciprocating agitator driven by a hydraulic ram in which the ram is used to press the agitator against the fabrics being cleaned to press the cleaning fluid or rinsing fluids therefrom.

Still another object is to provide a novel control for the valve which directs the flow of hydraulic fluid to the fluid chamber of a hydraulic ram whereby the direction and limits of reciprocation of the piston within the cylinder may be positively and selectively regulated.

Other and further objects of this invention will appear from the following description:

In the accompanying drawings, which form a part of the instant specification and are to be read in conjunction therewith, and wherein like reference numerals are used to indicate like parts in the various views,

Fig. 1 is a side elevation of a washing machine embodying this invention with parts broken away for clarity,

Fig. 2 is a view taken along the line 2—2 in Fig. 1 in the direction of the arrows,

Fig. 3 is a side elevational fragmentary view of a portion of the trip mechanism, on an enlarged scale, shown in Fig. 1,

Fig. 4 is a view taken along the line 4—4 in Fig. 3, in the direction of the arrows,

Fig. 5 is a view taken along the line 5—5 in Fig. 3 in the direction of the arrows,

Fig. 6 is an enlarged fragmentary sectional view of the drain of the washer shown in Fig. 1,

Fig. 7 is an enlarged side elevational view of the hydraulic ram and valve assembly shown in Fig. 1,

Fig. 8 is a view taken along the line 8—8 in Fig. 7 in the direction of the arrows,

Fig. 9 is a view taken along the line 9—9 in Fig. 8 in the direction of the arrows,

2

Fig. 10 is a view taken along the line 10—10 in Fig. 8 in the direction of the arrows, and

Fig. 11 is an enlarged perspective view of the plug valve 34.

It is believed that an understanding of the invention will be facilitated by a brief discussion of the major parts or assemblies of the machine. The washing machine may be considered to comprise 3 major portions or parts, namely the washer unit, the hydraulic ram or power unit, and the valve assembly and trip mechanism therefor which controls the flow of hydraulic fluid to the ram. For convenience, the description of the invention will deal with these three major parts separately in the order indicated.

Referring now to the drawings, the washer compartment comprises a rectangular outer tub or receptacle 11. Spaced somewhat from the rear wall of the tub and shown at the left of Fig. 1 is a vertical partition 12 suitably fastened to the side walls of the tub and forming a chamber at the rear of the tub with a drain 11a in its bottom. This chamber facilitates drainage of the washing fluid from the washing machine and also of the discharge of hydraulic fluid from the power unit. It is to be understood that this chamber may be formed by a tube or other separating means in place of partition 12. At the bottom of the partition is a drainage port 12a communicating with the interior of the washing machine through which washing or rinsing fluid may drain when the valve plate 13 is raised. This valve arrangement is detailed in Fig. 6. The valve plate 13 is hinged or pivoted at 14 and is manipulated by a thumb screw and stem 15 threaded to and extending through the rear wall of the washer tub. The inner end of stem 15 is suitably fastened to the valve plate 13 and is adapted to positively hold the plate in its vertical or closed position seating against the partition 12 adjacent port 12a.

Interliner or fabric receptacle 16, of lesser height than the tub, has a perforate bottom portion 16a. The interliner is held in spaced relation to the bottom of the tub by supports 17 and the walls of the tub by spacer rings 16a which may be formed integral with the interliner. The interliner is preferably removable to facilitate cleaning of the machine.

The tub has a cover plate 18 hinged to the rear of the tub at 19 and equipped with a fastener 20 at its front edge.

To agitate the cleaning fluid within the washer during operation, a perforate agitator plate 21 is mounted for vertical reciprocation within the

interliner 16. This plate is carried on the lower end of a connecting rod 22 extending through cover plate 19 and fastened at its other end to the driving member or piston of the hydraulic ram.

Coming to the power unit, it is seen by reference to Fig. 1 that the ram comprises a cylinder 23 mounted on the cover plate 18. This cylinder is of the usual type and is best shown in Fig. 7. The driving piston is mounted for reciprocation within the cylinder and is fastened to the upper end of connecting rod 22. The piston includes two discs 24 with central apertures. The discs are held in clamping relationship with two washers 25 of suitable material such as leather, rubber, synthetic rubber, fabric or the like. Thus the piston is reciprocated by alternately introducing hydraulic fluid below or above the piston. The agitator plate obviously reflects this motion and circulates the cleaning fluid in the washer tub. The hydraulic fluid enters and is discharged from the cylinder 23 through ports 26 and 27 adjacent the top and bottom of the cylinders, respectively, depending on the direction of travel of the piston.

Turning now to the assembly for controlling the flow of hydraulic fluid to the ram, it will be seen that this mechanism comprises a fluid actuated control valve, a mechanically manipulated valve and a trip mechanism. The fluid operated valve controls the flow of power fluid to the hydraulic ram. The mechanically manipulated valve controls the flow of actuating fluid to the fluid operated valve. The trip mechanism serves to mechanically trip the latter valve and is responsive to the position of the ram's driving member or the agitator plate 21.

The fluid operated valve and the mechanical valve are both housed in a casing 28 having adjacent chambers or cylinders 28a and 28b. Hydraulic fluid enters both chambers through an inlet port 28c, best shown in Fig. 19 which communicates with a source of hydraulic fluid supply through conduit 29. Chamber 28a has an upper port 30 communicating through a connection 31 with port 26 in the top of the ram cylinder and a lower port 32 communicating through pipe 33 with port 27 adjacent the bottom of the ram cylinder. These connections serve to alternately supply power fluid to opposite ends of the ram piston as well as to discharge expended power fluid from the ram cylinder.

A valve plug 34 within the chamber 28a is adapted in operation to permit flow of hydraulic power fluid through one of these ports at any given time. A recess or groove 34a in the periphery of the plug is adapted to connect the other of said ports 30 and 32 with a discharge port 35 and discharge line 36. Thus, with plug 34 in a raised position as shown in Fig. 8, power fluid enters chamber 28a through port 28c and flows past the tapered edge of plug 34 adjacent port 28c into the lower portion of the cylinder, thence through port 32 line 33 and into the lower portion of the ram to force the driving member of the ram to its raised position. During this time, fluid in the upper portion of cylinder 23 of the ram is forced through connections 26, 31, port 30, groove 34a, discharge port 35 and discharge line 36, into the chamber formed by partition 12 in the rear of the washer tub 11 and through drain 13 therefrom. When plug valve 34 is shifted to its lower position flow of hydraulic driving fluid is reversed to force the driving member of the ram toward a lowered position.

To hold plug 34 in alignment in cylinder 28a, a nut or plug 37 in casing 28 fits an axial groove 34b in the valve plug.

This plug valve 34 is fluid actuated by means of a connecting rod 38 fastened to a piston 39, operative in a cylinder 40 mounted above cylinder 28a. A stuffing box 41 surrounds rod 38 and provides a seal between cylinder 40 and chamber 28a. This piston and rod is hydraulically driven to operate plug valve 34. The upper portion of cylinder 40 is connected by conduit 42 with the lower portion of cylinder 28b. Conduit 43 communicates between the lower portion of cylinder 40 and the upper portion of cylinder 28b. Another valve element 50 having the same shape as valve plug 34 is reciprocally mounted within cylinder 28b. This valve element controls the flow of hydraulic fluid to and from cylinder 40 to actuate the power fluid control valve. This is accomplished in a manner similar to that just described in connection with supplying the hydraulic driving fluid to the ram. In other words, the recess 50a in element 50 of the mechanically manipulated valve alternately connects one of the conduits 42 or 43 to the discharge line 36 in which case the other conduit communicates with the source of hydraulic fluid by reason of the tapered side of the plug to supply hydraulic fluid to drive piston 39. Alignment of element 50 within chamber 28b is effected by bolt 37 operating in the axial groove 50b in the periphery of element 50.

Mechanically manipulated valve element 50 is fastened to the lower end of link 44 which extends through the top of cylinder 28b. Obviously raising or lowering of this link will move the mechanically manipulated valve resulting in a shifting or tripping of the fluid actuated control valve which regulates the flow of power fluid to the ram. This manipulation is accomplished by a trip mechanism comprising an elongated slotted member 45 fastened at its lower end to connecting rod 22 adjacent plate 21 and extending above the cover plate 18 of the washer tub.

A novel means is provided to engage and disengage link 44 and slotted member 45. This means includes a slide member 46 slidably mounted on member 45. This slide loosely receives one end of lever arm 47 pivoted on bracket 48. Manual manipulation of lever 47 causes slide 46 to be raised or lowered. This is effected when the end of arm 47 abuts either the upper or lower edge of the slide, dependent upon the direction of movement of arm 47 about its pivot. Link 44 has a depending section 44a which is turned outwardly at its lower extremity as at 44b. This outwardly turned portion forms a pin which penetrates an axial slot in back of slide 46 and which may selectively engage any of the slots of member 45. A cross pin 49 carried by pin 44b engages the back portion of slide 46. By reference to Fig. 3, this back or left hand portion of the slide is seen to have a corrugated shape so that pin 44b may penetrate within a selected slot of member 45 when the cross pin 49 resides in the valley of the corrugated surface. On the other hand, when the slide 46 is shifted so that cross pin 49 engages either crest in the corrugated back of the slide, pin 44b is disengaged from the slots of member 45. It is seen that pin 44b extending through the slot of slide 46 limits the amount that the slide may be raised or lowered by the lever 47.

With pin 44b engaged in a selected slot of member 45 the link 44 is shifted on engagement

with either extremity of the slot of member 45. This shift of link 44 in turn manipulates the mechanically manipulated valve element 50 which in turn reverses the fluid actuated valve 34 reversing the flow of power fluid into and from the ram. By engaging pin 44b in any selected slot of member 45 reciprocation of the ram driving member and consequent reciprocation of the agitator within the washer is confined to predetermined limits. When pin 44b is disengaged from any of the slots of member 45, the driving member of the ram will continue in one direction until it reaches the extremity of cylinder 23 toward which it is travelling. The driving member then ceases to move until the valve assembly is tripped. Manipulation of lever 47 to shift slide 46 effects a tripping of the mechanically manipulated valve as pin 44b is engaged by the extremity of the slot of said slide.

In operation the driving member of the ram is placed in a raised position. In this position the cover plate 18 may be tilted backwardly to give access to the washer tub when fastener 25 is released. The desired amount of water or other cleaning fluid is run into the washer tub and the materials to be cleaned are placed within the interliner. Cover plate 18 is then closed and fastener 20 is put in place. Lever 47 is then manipulated to raise slide 46, thus tripping valve element 50 of the mechanically operated valve to a raised position. This permits the flow of hydraulic fluid into the upper portion of cylinder 40 driving piston 39 to its lowered position thus shifting the valve plug 34 of the fluid control valve to its lower position in cylinder 28a. Piston 39 has but a small distance to travel and this distance is traversed in a fraction of a second, resulting in substantially snap action of the valve. This directs the driving fluid to the top of the ram driving member, forcing it downwardly and the fluid in the lower portion of cylinder 23 is discharged through connection 27, pipe 33, port 32, discharge port 35, and discharge line 36 into the discharge chamber in the rear portion of the washer tub and thence to a suitable disposal through drain 11a. This results in a downward movement of the ram driving member, agitator 21 and slotted member 45. As the slotted member moves downwardly slide 46 is held in a position to disengage pin 44b from the slots of the member until the slot corresponding to the level to which it is desired to operate the agitator is reached. Then the pin 44b is allowed to engage that slot.

With pin 44b engaging a selected slot the valve assembly is automatically tripped each time either extremity of the slot engages the pin 44b whereby the agitator is reciprocated between the desired level within the interliner of the washer tub. It will be seen that member 45 continues to move in a given direction until the fluid actuated valve is tripped so this action is positive, the power fluid supplying sufficient power to cause movement of pin 44b and link 44 to trip the mechanically actuated valve. This action is continued until the materials are believed to be clean. During the cleaning operation the agitator thoroughly circulates the cleaning fluid, causing it to pass through the materials or fabrics to be cleaned. The position of the interliner is such that the fluid is caused to surge through its perforate bottom and the space between the interliner and washer tub 11 overflowing the upper edge of the interliner and

washing over into the interior of the interliner.

When this has been continued for a sufficient time, to cleanse the materials or fabrics, drain plate valve 13 is raised by manipulation of the thumb screw and stem 15 permitting cleaning fluid to drain from the washer. When the tub is drained, pin 44b is disengaged from slotted member 45 when the member is travelling in a downward direction. The agitator plate then continues in its downward direction until the materials to be cleaned are engaged by the perforate bottom 16a of the interliner and the perforate agitator 21. This places the materials in a squeezing relationship to agitator 21 and the perforate interliner bottom forcing substantially all of the cleaning fluid therefrom. Plate 13 is then closed and rinsing fluid is introduced into the tub. The agitator is reciprocated for a short time and the drainage and squeezing operation is repeated. This rinsing operation may be repeated as often as desired and when completed, the agitator is caused to assume its upward position, cover 18 is opened and the clothes removed in a substantially dry condition.

25 It will be seen that the objects of this invention have been accomplished. There has been provided a washing machine driven by a hydraulic ram which may be operated by simple manipulation of a control member. The ram is such that the agitator plate may be reciprocated between selected levels of the washer tub. The construction is such that a mechanically actuated valve controls the flow of hydraulic fluid to actuate the main control valve which in turn regulates the flow of hydraulic fluid to the ram. The action of the ram is positive as the valve is completely tripped by a positive force so that during operation no dead center is encountered. The agitator and interliner arrangement is such that the cleansing fluid is thoroughly circulated and forced through the fabrics to be cleaned.

45 From the foregoing it will be seen that this invention is one well adapted to attain all of the ends and objects hereinabove set forth, together with other advantages which are obvious and which are inherent to the construction.

50 It will be understood that certain features and subcombinations are of utility and may be employed without reference to other features and subcombinations. This is contemplated by and is within the scope of the claims.

55 As many possible embodiments may be made of the invention without departing from the scope thereof it is to be understood that all matter herein set forth or shown in the accompanying drawing is to be interpreted as illustrative and not in a limiting sense.

Having described the invention what is 60 claimed is:

1. A trip mechanism for and in combination with a fluid actuated valve adapted for use in regulating the flow of power fluid to a hydraulic ram having a driving member, said trip mechanism comprising a mechanically manipulated valve operable to control the flow of actuating fluid to the first valve, connections between the hydraulic ram and the second valve adapted to actuate said valve, the connections including a 65 member having a series of slots and connected with the driving member of the ram, a link connected to the second valve and selectively engageable with the slots of said member whereby the driving member of the ram may be reciprocated between selected limits.

2. In a washing machine of the type having a tub with a reciprocating agitator therein, a fluid driven ram suitably connected to the agitator and a valve for directing the flow of fluid to the ram the improvement which resides in the combination therewith of a trip mechanism for said valve, and a releasable connection between the trip mechanism and said agitator, said connection including a plurality of sets of stops carried by one, and a part carried by the other adapted to be moved into and out of position between the stops of any set, to provide for limited relative reciprocal movement between the trip mechanism and agitator whereby the trip mechanism may be actuated by a selected set of said stops to control the level of reciprocation of the agitator within the tub.

3. In a fluid power mechanism a cylinder with a piston mounted for reciprocation therein, a fluid actuated valve operable upon actuation to supply power fluid to the cylinder first on one side of the piston and then on the other side of the piston, a mechanically operated valve controlling the flow of actuating fluid to the first valve, a connecting means between the piston and second valve including a link secured to one and an elongated member secured to the other, a plurality of spaced apart stops distributed along the elongated member, the link having a part adapted to reside between two of said stops providing for limited relative movement between the link and member and means for selectively retracting said part from and advancing said part into position between two of said stops whereby with the link part residing between two stops movement of the piston shifts the second valve upon each engagement of the link part with one of the stops to actuate the first valve and thereby reverse the direction of travel of the piston.

4. In a fluid power mechanism a cylinder with a piston mounted for reciprocation therein, a fluid actuated valve operable upon actuation to supply power fluid to the cylinder first on one side of the piston and then on the other side

5 10 15 20 25 30 35 40 45 of the piston, a mechanically operated valve controlling the flow of actuating fluid to the first valve, a connecting means between the piston and second valve including a link secured to one and a connecting member secured to the other, spaced apart stops on the member, a part on the link adapted to reside between the stops providing for limited relative movement between the link and member and means for selectively retracting said part from and advancing said part into position between the stops whereby with the link part residing between the stops movement of the piston shifts the second valve upon each engagement of the link part with one of the stops to actuate the first valve and thereby reverse the direction of travel of the piston and retraction of the link part from between the stops permits the piston to move to and stop in one end of the cylinder.

5. The combination of claim 4 wherein the means for operating the link part is connected to the second valve and is operable to trip the same, when the piston is stopped, to start the power mechanism.
